(57) **CLAIM**

The ornamental design for an automated teller machine, as shown and described.

DESCRIPTION

FIG. 1 is a perspective view.

FIG. 2 is a front view.

FIG. 3 is a rear view.

FIG. 4 is a left side view that is symmetric with a right side view.

FIG. 5 is a plan view; and,

FIG. 6 is a bottom view.

The combined shape and figure of the automated teller machine is claimed as the main point of creation in the design application.
